Primary Examiner — Amber R Stiles*Assistant Examiner* — Tia Ruth-Renee Polidori(74) *Attorney, Agent, or Firm* — Calderone McKay, LLC(57) **CLAIM**

The ornamental design for a straw bottle as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of my new design for a straw bottle;

FIG. 2 is a left side elevation view thereof;

FIG. 3 is a front elevation view thereof;

FIG. 4 is a right side elevation view thereof; and,

FIG. 5 is a top plan view thereof.

The Portions of the straw bottle shown in broken lines form no part of the claimed design.

1 Claim, 4 Drawing Sheets
